UNITED STATES PATENT OFFICE.

SAMUEL GRISWOLD, OF CAMP POINT, ILLINOIS.

PENHOLDER.

1,173,797.

Specification of Letters Patent. Patented Feb. 29, 1916.

Application filed October 30, 1913. Serial No. 798,241.

To all whom it may concern:

Be it known that I, SAMUEL GRISWOLD, a citizen of the United States, and a resident of Camp Point, in the county of Adams 5 and State of Illinois, have invented a new and Improved Penholder, of which the following is a full, clear, and exact description.

My invention provides a penholder having at its forward end a sheath or case adapted to coact with the front end of the holder, to hold a pen, the case being removable, and there being provision within the case and rearward of the pen-holding 15 front end, whereby the pen may be held at the front in proper position for writing, or may be removed and housed within the sheath and held therein when the pen is not required for use. The invention includes 20 also a novel absorbent cushion covering the sheath, the covering consisting of corn pith in tubular form suitably united to the exterior of the sheath.

It is well known that blotting paper, 25 while readily absorbent of ink, soon becomes useless owing to the pores becoming filled with the dried ink, and therefore blotting paper, after short use, must be discarded. Similarly, cork, when it has taken up any 30 appreciable quantity of ink, will not absorb, or at least will not readily absorb additional ink after the first ink has dried. This characteristic is materially less, if not wholly absent from the corn pith, in which 35 the ink runs so readily from the disposing point that the pores are maintained substantially open, and repeated applications of ink are possible at the same surface of the pith.

40 The invention will be more particularly explained in the specific description herein-after to be given.

Reference is to be had to the accompanying drawings forming a part of this specification, in which similar characters of reference indicate corresponding parts in all the views.

Figure 1 is a longitudinal elevation of a penholder embodying my invention; Fig. 2 50 is a side elevation, the pen case or sheath and the pens being omitted; and Fig. 3 is a cross section on an enlarged scale, on the line 3-3 of Fig. 1.

In forming a penholder and appurte- 55 nances in accordance with my invention, the holder 10 has formed thereon or secured

thereto, a forwardly extending section 11 of reduced diameter, the front end of which terminates short of the extreme front end of the holder. A case or sheath 12 in the 60 form of a sleeve is removably fitted over the front end of the holder, the rear end of the sleeve overlapping the holder at the back of the reduced forward extension 11, as at 13, and fitting friction tight. The front end 65 of the handle beyond the reduced portion 11 has a head 14, preferably cylindrical, of a diameter sufficiently less than the internal diameter of the sleeve to accommodate the shank 15 of a pen 16, between the said head 70 and the sheath, to hold the pen tightly in position for writing.

Rearward of the front end of the handle provision is made for housing a pen or pens within the sheath, and between the same and the reduced portion 11 of the handle. For the purpose I form the handle with an enlargement 17, which defines the forward end of an annular chamber 18 surrounding the reduced portion 11. The enlargement 17 is 80 approximately the same in diameter as the internal diameter of the sheath, so as to constitute a closure for the annular chamber 18.

Within the chamber 18, I provide means 85 to retain a pen or pens 16^a; in the present instance said means consists of a band 19 concentric with the reduced portion 11, and adapted to slide longitudinally thereof in the chamber 18. The said band is adapted 90 to be moved to the position indicated in full lines in Fig. 1, to encircle the pen or pens 16^a and tightly hold the same against the reduced portion 11 of the holder, or said band may be slid to a rearward position, 95 as indicated by dotted lines, so that the pens 16^a may be removed or replaced, it being understood that the sheath 12 is removed in placing a pen in the chamber 18 or removing it therefrom.

Forward of the enlargement 17, the holder is preferably made tapering, as at 20, so that the head 14 will not engage the shank 15 of the pen 16 along the whole length of the latter, the head more effectively gripping 105 the pen when there is a free portion of the shank 15 at the rear of the head.

By the described construction it will be obvious that a pen may be placed in the holder to project from the front of the 110 sheath in position for writing, as at 16 in Fig. 1, and that the said pen and the sheath

may be removed and the pen housed similarly to the pen 16^a; thus provision is made for protecting the pen when not in use, as when being carried in the pocket, or when being placed in a desk.

The sheath or case 12 has a cylindrical covering 12^a of resilient, absorbent corn pith, which forms a cushion to the fingers of the user, and moreover serves to absorb 10 and take up any ink that may result from too deep a dipping of the pen in the ink well, or any ink that may accidentally adhere to the finger tips. The corn pith cushion I have found possesses special absorbent 15 properties as applied to a penholder, in that any ink coming in contact therewith at the front end will be instantly absorbed and does not appreciably harden the corn pith, or destroy its resiliency.

20 Having thus described my invention, I claim as new, and desire to secure by Letters Patent:

25 A penholder, having a removable case, the holder having an elongated reduced portion terminating a short distance from the front end of the holder, and a sheath fitting

the holder at a point rearward of the said reduced portion, the holder furthermore having a head at the front end coaxing with the interior surface of the front end of the sheath to retain a pen in position for writing, and having an enlargement rearward of the said head, at the forward terminal of the mentioned reduced portion, there being an annular chamber surrounding the reduced portion of the holder within the sheath adapted to accommodate a pen, and the mentioned enlarged portion rearward of the head forming a closure for said chamber, the holder at a point between the head and the enlarged portion being of less diameter than the head, and means on the holder within the annular chamber to retain a pen.

In testimony whereof I have signed my name to this specification in the presence of two subscribing witnesses.

SAMUEL GRISWOLD.
